(57) **CLAIM**

The ornamental design for a clip, as shown and described.

DESCRIPTION

FIG. 1 is a right side elevation view of a clip, the broken lines on the right side are omitted for ease of visibility.

FIG. 2 is a left side elevation view of a clip, the broken lines on the left side are omitted for ease of visibility.

FIG. 3 is a front elevation view of the clip of FIG. 1.

FIG. 4 is a rear elevation view of the clip of FIG. 1.

FIG. 5 is a top plan view of the clip of FIG. 1.

FIG. 6 is a bottom view of the clip of FIG. 1.

FIG. 7 is an isometric view of the clip of FIG. 1; and,

FIG. 8 is a cross-sectional right side elevation view of the clip of FIG. 1, taken on the line 8-8 in FIG. 5.

Portions of FIGS. 1 through 8 are shown in broken lines illustrating portions of the article that form no part of the claimed design.

1 Claim, 8 Drawing Sheets**FIG. 1**

FIG. 2

FIG. 3

FIG. 4

FIG. 5

FIG. 6

FIG. 7

FIG. 8
